UNITED STATES PATENT OFFICE.

STEFANO CHIARELLO, OF BROOKLYN, NEW YORK.

CAR STAKE.

Application filed August 25, 1927. Serial No. 215,446.

This invention relates to improvements in car stakes and more particularly to side folding car stakes for flat and gondola railway cars.

5 The primary object of the invention is to provide a side folding car stake which is extremely simple and durable in construction as well as efficient in use.

Another object is to provide an improved 10 side folding car stake embodying simple and efficient means for releasably maintaining the same in operative position.

15 A further object is to provide an improved side folding car stake of the above kind having simple and efficient means whereby the load binding chain may be readily adjusted to the height of the load.

20 Other objects will become apparent as the nature of the invention is better understood, and the same consists in the novel form, combination and arrangement of parts hereinafter more fully described, shown in the accompanying drawings and claimed.

25 In the drawings, wherein like reference characters indicate corresponding parts throughout the several views,

Figure 1 is a fragmentary longitudinal section of a gondola car equipped with a 30 side folding stake constructed in accordance with the present invention, the stake being in operative position and shown in side elevation as seen looking toward the inner side thereof;

35 Figure 2 is a view looking toward the left of Figure 1;

Figure 3 is a horizontal section on line 3—3 of Figure 1;

40 Figure 4 is a vertical section on line 4—4 of Figure 1;

Figure 5 is a view similar to Figure 1 of a modified form of stake constructed in accordance with the present invention;

45 Figure 6 is a view looking toward the left of Figure 5; and

Figure 7 is a horizontal section on line 7—7 of Figure 6.

The form of the invention shown in Figures 1 to 4 inclusive embodies a stake member 6^a adapted to be vertically positioned at the inner side of the side wall 14^a of the car for projecting above the upper edge of the latter when operatively positioned, and this stake member 6^a is in the form of an open ended rigid metallic tube of rectangular cross-section as shown clearly in Figure 3.

Provided in the inner side wall of the stake section 6^a and extending from the upper end of the stake member to a point adjacent the upper edge of the wall 14^a 60 of the car is a longitudinal elongated slot 16^a in which is slidably fitted an H-shaped slide block 17^a to which is attached one end of a load binding chain 18^a. This load binding chain is adapted to be connected to a slide block of a similar opposed stake mounted upon the other side of the car, and as the slide blocks are freely movable in a vertical direction, the load binding chain 18 may be readily adjusted to the height of 70 the load. In order that the slide block 17^a may be prevented from accidentally passing out of the upper end of the slot 16^a, the upper end of the latter is preferably closed by means of a plate P secured upon the 75 inner wall of the stake member and extending across the upper end of the slot as shown clearly in Figure 1.

The stake member 6^a is attached to the side wall 14^a of the car by means of a pivot 80 bolt B which passes through opposed vertically elongated slots S provided in the lower end of the stake member 6^a. In this way, the stake is attached to the side of the car so as to permit the stake member to be 85 raised and lowered and to be swung parallel with the side of the car. Thus, by raising the stake member 6^a, the lower end of the latter may be disengaged from the socket member M on the bottom or floor F 90 of the car so that said stake member may be subsequently swung parallel with the side of the car downwardly to a substantially horizontal folded position. When thus folded, the stake member will be out of the way 95 as desired when not in use. On the other hand, when the stake is desired for use, it may be readily swung upwardly to a vertical position and then lowered while vertically disposed so that the squared lower end of 100 the stake member 6^a is brought into flat engagement with the floor within the socket member M, whereby the stake member is effectively maintained in its vertical operative position. Hooks 31 are pivoted to the 105 sides of the stake member 6^a for detachable engagement with the side wall 14^a of the car so as to hold the stake member against inward strains.

The form of stake shown in Figures 5 to 110 7 inclusive is similar to that shown in Figures 1 to 4 inclusive, except that the stake

member 6^a is pivotally mounted for swinging from operative to inoperative position, and vice versa, by being pivotally mounted at its lower end between the spaced upstanding walls of a U-shaped bracket 30 rigidly secured upon the floor F of the car at the inner side of the wall 14^a of the latter, the outwardly projecting hooks 31 being pivoted to the sides of the stake member 10 6^a and engageable over the upper edge of the wall 14^a of the car, whereby the stake member 6^a is held to the car wall 14^a and retained in vertical operative position. As shown, the upstanding walls of the bracket 15 30 support a transverse horizontal pivot bolt B upon which the lower end of the stake member 6^a is hinged so that said stake member may be swung in a plane parallel with the side of the car to a vertical operative or 20 a horizontal inoperative position. Naturally, the hooks 31 are swung upwardly out of engagement with the car wall 14^a in order to permit the stake member 6^a to be swung downwardly to its inoperative horizontal position. Further, the bolts B of both forms 25 of the invention may be equipped with nuts 32 that may be tightened, if desired, to retain the stake member in either of its positions. Otherwise, the form of the invention 30 shown in Figures 5 to 7 inclusive is similar to that of Figures 1 to 4 inclusive in that the inner wall 6^a has the elongated longitudinal slot 16^a, in which the slide block 17^a is slidably mounted, the load binding chain 18^a 35 being attached to this slide block, and the latter being prevented from passing out of the upper end of the slot 16^a by means of the plate P.

From the foregoing description it is believed that the construction and operation 40 as well as the advantages of the present invention will be readily understood and appreciated by those skilled in the art.

Minor changes may be made without departing from the spirit and scope of the 45 invention as claimed.

What I claim as new is:—

1. In a car stake, a hollow stake member of rectangular cross-section adapted to be mounted at a side of the car and to assume 50 a raised vertical operative position, said stake member having a longitudinal elongated slot in the inner wall thereof, an H-shaped slide block slidably fitted in said slot for vertical adjustment relative to the stake member, a load binding chain attached to said slide block, and means to hold said stake member in its raised operative position.

2. In a car stake, a hollow stake member 60 of rectangular cross-section adapted to be mounted at a side of the car and to assume a raised vertical operative position, said stake member having a longitudinal elongated slot in the inner wall thereof, an H- 65 shaped slide block slidably fitted in said slot for vertical adjustment relative to the stake member, a load binding chain attached to said slide block, means to hold said stake member in its raised operative position, and 70 hooks pivoted to the sides of the stake member and engageable with the side wall of the car to hold the stake member against inward strains.

In testimony whereof I affix my signature.

STEFANO CHIARELLO.
